UNITED STATES PATENT OFFICE.

FRANK R. WATERMAN, OF MEDFORD, MASSACHUSETTS, ASSIGNOR OF ONE-HALF TO
ERNEST J. HALL, OF BROCKTON, MASSACHUSETTS.

GARMENT-CLASP.

1,113,522.

Specification of Letters Patent.

Patented Oct. 13, 1914.

Application filed December 14, 1911. Serial No. 665,605.

To all whom it may concern:

Be it known that I, FRANK R. WATERMAN, a citizen of the United States, residing at Medford, in the county of Middlesex and 5 Commonwealth of Massachusetts, have invented a new and useful Improvement in Garment-Clasps, of which the following is a specification, reference being had to the accompanying drawing.

10 My invention relates to that type of clasp which is provided with a tongue or spring clip adapted to contact with a stud and to retain the stud in position, it being the special object of my invention to make a tongue 15 which will be readily maintained in position and which will not catch in the garments of the wearer.

In the drawing Figure 1 is a top view of my device in operative position. Fig. 2 is a 20 sectional side view on line 2—2 of Fig. 1.

Referring now more specifically to the drawing, A is a plate bearing the rounded stud a which is adapted to enter the large 25 end of the slot b of the plate B and to be drawn back into operative position, as shown in the drawing, where the narrowness of the slot b will prevent the enlarged top of the stud a from passing downwardly through it. The spring-tongue b¹ tends to retain the stud 30 a in operative position and is shown cut out of the plate B and rolled back at its extremity to form the rounded end b² which contacts with the stud a upon its upper surface in a manner whereby it may be forced up- 35 wardly by movement of the stud a and allow the stud a to pass. The tongue b¹ is also provided with lugs b³, b⁴, preferably stamped

out integral therewith, which upon the arching of the tongue b¹ are brought to bear firmly by spring tension upon the plate B, 40 thus positively retaining the tongue b¹ in its normal operative position and preventing it from becoming depressed into the slot b and bearing improperly upon the stud a. By the holes c the plates A and B may be 45 fastened to the garment or other thing whereon the device is employed.

It will be readily seen that my device contains no element which can be caught in the garment of the wearer, or otherwise, and be 50 displaced or bent out of its proper adjustment.

Having thus fully described my invention what I claim is—

In a device of the character specified, a 55 member bearing a stud, a slotted member adapted to receive said stud, a spring tongue integral with said slotted member and adapted to engage the side of the head of said stud and hold the same in operative position, 60 and provided with lugs, said spring tongue being formed by the cutting of the slot in said slotted member, and the lugs thereon being adapted by the arching of said spring tongue and the spring pressure thereof to 65 bear normally upon said slotted member.

In testimony whereof I have hereunto set my name in the presence of two subscribing witnesses.

FRANK R. WATERMAN.

Witnesses:

DANFORTH W. COMINS,
JOHN F. MULLEN.
